UNITED STATES PATENT OFFICE.

ANDREAS THEE, OF WURZBURG, GERMANY.

BUILDING BLOCK OR SLAB.

Application filed September 11, 1922. Serial No. 587,551.

To all whom it may concern:

Be it known that I, ANDREAS THEE, citizen of the German Republic, residing at Wurzburg, Worthstrasse 40, Germany, have invented certain new and useful Improvements in Building Blocks or Slabs, of which the following is a specification.

My invention relates to improvements in building blocks or slabs, and more particularly in building blocks or slabs which are in the form of an irregular H and are adapted to be composed into hollow insulating walls. In order to produce with building blocks of this type a good joint between adjacent blocks when laying the same into a wall it has been proposed to construct the side portions thereof with equal lengths but offset from each other, one side portion at each end of the block projecting beyond the other one. The object of the improvements is to produce a block of the class referred to which can be laid with a proper joint also at the corners of the wall, and I attain this object by constructing the side portions and the web portion of the block with specific relative dimensions, such as will be explained hereinafter.

In order that my invention be more clearly understood an example embodying the same has been shown in the accompanying drawing, in which the same reference characters have been used in all the views to indicate corresponding parts. In said drawing,

Fig. 1, is a plan view showing the building block or slab,

Figs. 2 to 6, are similar plan views showing forms of the block derived from the basic form shown in Fig. 1,

Figs. 7 and 8, are respectively an elevation and a vertical section showing a part of a wall made from my improved block,

Figs. 9 and 10, are plan views showing two superposed courses of blocks or slabs laid in a wall, and

Figs. 11 and 12, are similar plan views showing a modification.

As appears from Fig. 1 the building block consists of a web portion a and side portions marked as a whole d and d' . The side portions are equal in length, but they are offset with relation to each other, the length of the part b^2 in each side portion being larger than that of the part b' . In a block constructed according to my invention the web portion a is square in plan

view and the length of its sides is equal to the thickness of the side portions d and d' , which thickness is one third of the length of the side portions d and d' . The short parts b' of the side portions, which are located at opposite sides of the web portion a have a length equal to one sixth of the total length c of the side portions d and d' , and the length of the long parts b^2 is equal to one half of the length c . The mid-parts b of the side portions have the length $\frac{1}{3}c$, and they have the same dimension as the web portion a . Therefore the total breadth of the block, which is the sum of the lengths of the parts b , a , and b , is equal to c .

In Fig. 1 I have shown dotted lines indicating how other forms of blocks are derived from the basic form, which forms have been shown in detail in Figs. 2 to 6. In the example shown in Fig. 2 the projecting parts of the side portions located at one side of the web portion have been omitted. In the modification shown in Fig. 3 at one side of the web portion the short part b' of one of the side portions is omitted and the length of the long part is reduced by $\frac{1}{3}c$ the remainder having the length of the part b^2 . In the example shown in Fig. 4 the long part b^2 of the side portion is cut off at one side of the web portion a . Fig. 5 shows an example in which the long and the short parts b' and b^2 of one side portion and the long part of the other side portion have been omitted, and in Fig. 6 only the web portion a of the block is omitted so that in fact the block consists of two sectional blocks each having the length c and the thickness $\frac{1}{3}c$.

In Figs. 7 to 8 I have shown a wall built from my improved blocks. As appears more particularly from Figs. 9 and 10 consecutive courses of blocks are disposed so as to break joint throughout the side portions, and the web portions are placed one above the other so as to provide hollow insulating spaces. The course on which the beams e are supported is built from sectional blocks of the form shown in Fig. 6, which blocks cover the hollow spaces. The window sill is built from blocks of the form shown in Fig. 5, and the vault of the window is made from blocks of the form shown in Fig. 2.

In Figs. 11 and 12 I have shown two courses showing a modification of the joints at the corner. By using sectional blocks

of the form shown in Fig. 6 the blocks can be laid so as to break joint at the corner.

I claim:

1. A building block consisting of a web portion and parallel side portions, the side portions each having a length equal to three times the length of said web portion and each side portion projecting one half its length at one side of said web portion and one sixth its length at the opposite side thereof, the shorter and longer projections of said side portions being on the same side of said web.
2. A building block consisting of a web portion and parallel side portions, said por-

tions having the same thickness and said web portion being a cube, said side portions each having a length equal to three times the length of said web portion and each side portion projecting one half its length on 20 one side of said web and one sixth its length on the opposite side thereof, the shorter and longer projections being on the same side of said web.

In testimony whereof I affix my signature in presence of two witnesses.

ANDREAS THEE.
